ATTORNEY

UNITED STATES PATENT OFFICE.

ERWIN R. STOEKLE, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

Application filed September 12, 1921. Serial No. 500,016.

To all whom it may concern:

Be it known that I, ERWIN R. STOEKLE, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

This invention relates to electric switches and more particularly to switches of the fluid contact type.

In my Patent No. 1,492,584, dated May 15 6, 1924, is disclosed a switch mechanism adapted to control circuit by means of fluid contacts and at a relatively small expenditure of mechanical power, such mechanism being specially designed and constructed to 20 minimize deterioration of the switch parts due to the effects of possible arcing, and the present invention has among its objects that of providing an improved switch mechanism of the foregoing character wherein 25 certain of the aforementioned characteristics are still further accentuated.

Another object is that of providing such a switch which is adapted to maintain its utility and effectiveness substantially un- 30 impaired even after a considerable degree of structural deterioration due to arcing or the like.

Other objects and advantages will hereinafter appear.

In the accompanying drawing, wherein are illustrated certain of the embodiments 35 which the invention may assume in practice,

Fig. 1 is a vertical sectional view of a proposed construction thereof; while,

Fig. 2 is a similar view illustrating a modified construction.

Referring to Fig. 1 of the drawing, the same illustrates a switch comprising a hermetically tight supporting envelope or container 5 composed of insulating and heat resistive material such, for example, as pyrex glass and containing a quantity of conductive fluid 6, such for example, as mercury.

Said container is preferably of cylindrical or other circular contour and is interiorly provided with an integrally formed or rigidly secured bulb 7 arranged concen-

trically therewith and preferably spaced therefrom except at the region of attachment indicated at 8. Conductive terminals 9 and 10 are sealed within the outer walls of the container 5 preferably at terminally and centrally located portions thereof, the terminal 9 being arranged to penetrate the region 8 and within the bulb 7 as illustrated, whereas, the terminal 10 is arranged entirely without said bulb and both of said terminals are provided with portions arranged permanently below the level of the conductive fluid 6.

The bulb 7 is provided with a circumferentially located opening 11, the same being preferably spaced approximately equal distances from the submerged portions of the respective terminals 9 and 10 as illustrated and said opening serving when in the position illustrated to provide for physical and electrical continuity of the bodies of conductive fluid located respectively within and without the bulb 7. Said bulb is also preferably provided with a further opening 12 which may be of reduced diameter relative to that of the opening 11, the same being also located circumferentially of the bulb 7 and angularly displaced with reference to the opening 11 whereby said opening 12 is above the level of the conductive fluid under normal operating conditions of the device, the function of said opening being that of equalizing pressures within and without the bulb 7 particularly under conditions wherein the opening 11 may be completely submerged.

In practice the terminals 9 and 10 are preferably extended given or desired distances axially beyond the outer boundary of the container 5 and are terminally electrically connected with suitable conductive caps 13 and 14 as by soldering, welding or otherwise, said caps being in turn permanently secured to and about the respective terminal portions of the container 5 by cement or in any other desired or preferred manner.

The aforescribed mechanism is oscillatably supported and provided with external circuit connections preferably in the manner illustrated but optionally in any other suitable manner, whereas a suitable operating lever 15 is secured to the switch for oscillation thereof. Also where said lever is to be actuated mechanically throughout a

fixed angle the same is preferably arranged for angular adjustment relative to the switch structure to thereby provide for varying at will the angular positions of the lever at which circuit is respectively broken and re-established by the switch. In practice said lever is preferably mounted for angular movement relative to the switch structure as illustrated but is normally clamped there-to by means of a screw 16 whereas a suitable pointer and scale indicated generally at 17 are provided to facilitate accuracy of the angular adjustment.

The various parts being in the relative positions illustrated, it is obvious that the circuit through the switch is completed from terminal 9 to the conductive fluid and through that portion of the latter extending through the opening 11 to the conductive fluid without the bulb 7, thence to the terminal 10 and to the other side of the circuit. However, upon partial rotation of the container 5, such as to lift the opening 11 above the surface of the conductive fluid, it is apparent that the aforescribed circuit is broken suddenly between fluid surfaces, whereas, upon partial rotation of the switch in the opposite direction to the position illustrated or even somewhat beyond such position the circuit is re-established in a similar manner and similarly between fluid surfaces.

In practice it is preferable to exhaust the air, particularly the oxygen thereof, from the interior of the container 5 prior to sealing said container, for the purpose of preventing oxidation of the interiorly located conductive elements due to the effects of possible arcing, the space above the level of the conductive fluid being left substantially evacuated or optionally being filled with one of the known inert arc suppressing gases.

While the foregoing expedients are found to be largely effective in suppressing arcs incident to interruption of currents of relatively reduced value, nevertheless a certain degree of arcing may occur even under the aforementioned conditions where the value of the electrical energy to be broken is of relatively high magnitude. However, the aforescribed construction and arrangement serves to limit any deleterious effects of such possible arcing to those portions of the bulb 7 adjacent or contiguous to the opening 11, the outer container 5 being wholly unaffected, whereby even in the event of serious arcing adjacent the opening 11, such even as to effect a considerable degree of deterioration or disintegration of the material of the bulb 7 at or adjacent to such point, the hermetically tight seal is still maintained by means of the container 5 and the operativeness and efficiency of the device are either unaffected or not seriously impaired.

65 Referring now to Fig. 2 of the drawing,

the same illustrates a switch construction similar in most respects to that aforescribed. In this instance, however, the inner bulb 7^a is structurally independent of the container 5^a being on the other hand adapted to float within and to a large extent above the surface of the conductive fluid 6 as illustrated whereby in operation the mass of the parts which require to be moved physically is very materially reduced with a corresponding reduction in the operating force required.

In practice the terminals 9^a and 10^a are sealed within the walls of the container 5^a as aforescribed, said terminals having parts axially positioned with reference to said container 5^a and adapted to extend loosely into axially arranged openings of the bulb 7^a as illustrated, whereby said terminals comprise means for positioning and guiding said bulb to thereby maintain the latter substantially concentrically spaced within the container 5^a as illustrated. One or both of the terminals 9^a and 10^a may be preferably provided with parts such as 18 and 19 forming shoulders for preventing axial shifting of the bulb 7^a with reference to the container 5^a, whereas, said terminals are provided with conductive portions to be continuously immersed in the conductive fluid respectively within and without the bulb 7^a as aforescribed. A relatively small and light armature member 20 is secured to the bulb 7^a in spaced relation to the axis of oscillation thereof, whereas, a relatively small electro-magnet 21 is located outside the container 5^a in such relation as when subjected to a given degree of energization to attract said armature member for effecting rotation of the bulb into the position illustrated wherein circuit between the terminals 9^a and 10^a is established, whereas, upon de-energization of the electro-magnet the weight or buoyancy of the armature member 20 may be utilized for effecting reverse partial rotation of the bulb for interrupting the controlled circuit.

In practice the electro-magnet 21 is preferably mounted in a manner providing as illustrated for angular adjustment thereof in the plane of oscillation of the armature member 20 thereby providing for adjustment or calibration of the sensitiveness of response of the switch and also serving as a means for regulating the time element incident to response thereof.

From the foregoing it is apparent that each of the constructions aforescribed is adapted to the control of relatively high values of electrical energy by means of a minimum expenditure of mechanical power, whereas, each of the structures described is adapted to maintain its operativeness, utility and efficiency even following such prolonged or arduous service as to effect

considerable damage to the material employed in its construction since such damage can occur only at such points as not seriously to affect such characteristics of the 5 switch.

What I claim as new and desire to secure by Letters Patent is:

1. An electric switch comprising inner and outer containers, the outer container 10 comprising a hermetically sealed insulating envelope, a conductive fluid included within said envelope to extend within said inner container, terminals within said containers, and means for effecting rotation of said inner container while maintaining said outer container in fixed position for interrupting and re-establishing conductivity between the portions of said fluid within the respective containers.

2. An electric switch comprising inner and outer containers, the outer container comprising a hermetically sealed insulating envelope, a conductive fluid included within said envelope to extend within said inner container, terminals within said containers, means whereby electrical conductivity between the portions of the conductive fluid respectively within and without said inner container is interrupted and re-established 30 upon rotation of said inner container in opposite directions while said outer container remains stationary, and electro-magnetic means for effecting such rotation.

3. An electric switch comprising inner and outer containers, terminal devices for the respective containers, the outer container comprising a hermetically sealed insulating envelope, a conductive fluid included within said envelope and having a portion thereof located also within said inner container and adapted to be in electrically conductive relation with the fluid therewithout, said inner container having means whereby circuit between the portions of fluid therewithin and therewithout is interrupted and re-established upon partial rotation of said inner container in opposite directions, and electro-magnetic means for effecting said rotation in one direction only

while maintaining said outer container in 50 fixed position.

4. An electric switch comprising inner and outer containers, the outer container comprising a hermetically sealed integral insulating envelope, a conductive fluid included 55 within said envelope and having a portion thereof located also within said inner container, terminal devices penetrating said envelope and having portions to be continuously immersed within the conductive fluid 60 respectively within and without said inner container, the latter having means adapting the same upon partial rotation in opposite directions to respectively interrupt and re-establish conductivity between said terminal 65 devices, and electro-magnetic operating means for said inner container.

5. In an electric switch, the combination with a container and a quantity of conductive fluid therein, of an insulating member 70 adapted to float in said fluid, terminal devices to be electrically connected by said fluid, said terminal devices having means for maintaining substantially a predetermined space relation between said container and said insulating member and means to act upon said insulating member for controlling continuity of circuit between said terminal devices.

6. The combination with a hermetically 80 tight insulating container having a conductive fluid therein and also including a space substantially devoid of oxygen gas, of terminal devices penetrating said container and having portions to be continuously immersed in said fluid, an insulating bulb 85 included within said container to be supported by said fluid and to contain a quantity thereof, certain of the immersed portions of said terminal devices being located 90 within said bulb, said bulb having means providing for electrical continuity of the fluid inside and outside thereof and means to act upon said bulb for interrupting such continuity.

In witness whereof, I have hereunto subscribed my name:

ERWIN R. STOEKLE.
